UNITED STATES PATENT OFFICE.

ANTHONY DIXON BROGAN AND ANDREW MURRAY MALLOCH, OF FIRHILL,
GLASGOW, SCOTLAND.

DESIGN FOR PLATE-GLASS.

No. 39,185.

Specification for Design.

Patented March 10, 1908.

Application filed December 31, 1907. Serial No. 408,844. Term of patent 14 years.

To all whom it may concern:

Be it known that we, ANTHONY DIXON BROGAN and ANDREW MURRAY MALLOCH, subjects of the King of the United Kingdom of Great Britain and Ireland, residing at Firhill, in the city of Glasgow, county of Lanark, Scotland, have invented a new, original, and ornamental Design for Plate-Glass, of which the following is a specification, reference being had to the accompanying drawing, forming part thereof.

The figure is a plan view of part of a sheet of plate glass, showing our new design.

We claim:

The ornamental design for plate glass as shown.

ANTHONY DIXON BROGAN.
